BRAKING MEANS FOR PERFORATED MUSIC ROLLS.

1,406,430.

Specification of Letters Patent. Patented Feb. 14, 1922.

Application filed October 3, 1919. Serial No. 328,304.

To all whom it may concern:

Be it known that we, WILLIAM A. WATSON and WARNER EUSTIS, both citizens of the United States, residing, respectively, at 5 Malden and Newton, in the county of Middlesex and State of Massachusetts, have invented certain new and useful Improvements in Braking Means for Perforated Music Rolls, of which the following is a 10 specification.

This invention relates to braking means for perforated music rolls, and one of the objects of the invention is to provide braking means to contact with the surface of the 15 rolled music sheet in such way as to produce a decreasing braking action while the music sheet is being unwound in playing, and to produce a less braking action when the music sheet is travelling in a reverse direction in 20 rewinding it. Another object of the invention is to provide a gravitating brake which acts the more strongly the further it is moved away from a vertical position. Other 25 objects are to provide a practical and efficient brake for acting upon a perforated music sheet, both when it is moved in the playing direction, and in the rewinding direction.

These being among the objects of the present invention, the same consists of certain 30 features of construction and combinations of parts to be hereinafter described and then claimed with reference to the accompanying drawings illustrating one embodiment of the invention, and in which—

35 Fig. 1 is a front elevation, the parts being broken away, of a spool-box or a tracker-box of a player musical instrument with the invention applied.

Fig. 2 is a vertical section of the same, 40 showing the brake in action; and

Fig. 3 is a similar view enlarged, but parts being broken away and parts in elevation, said view showing more clearly the action of the brake.

45 Referring to the drawings, the spool-box or tracker-box 10, may be of any suitable construction, carrying the tracker 11, provided with suitable mountings for the spools 12 and 14 of the perforated sheet of music, 50 which spools are supported in a well-known manner by means of rotary carriers or shafts 13 and 15, said carriers being located so as to rotate said spools. The lower spool 14 constitutes the take-up spool in playing a

piece of music which is perforated on the 55 sheet carried by the removable spool 12, which then constitutes a let-off spool. As is well known, the spool 14 constitutes the let-off spool and the removable spool 12, constitutes the take-up spool in rewinding after 60 a piece of music has been performed.

A friction-shoe 16, is adapted to contact with the surface of the sheet of music which is rolled upon the spool or roll 12, and said shoe is carried by a member 17, which is 65 preferably pivotally hung from the upper end of the box 10, by means of brackets 18, one at each end of said member 17, and which brackets receive movable pivots 19. Preferably the pivoted or gravitating member 70 17 is formed from the upper half of the back of the spool-box, so that the member 17 serves two functions. The friction-shoe 16, is located at about the middle of the vertical dimension of the member 17 and extends substantially parallel with the length of the 75 spool 12, but is short enough so that it may move into the space between the flanges of said spool.

That edge of the shoe 16 which bears 80 upon the rolled web or sheet of music is preferably rounded at 20, so as to move smoothly over the surface of the roll, and so that the web or sheet may be unwound from the spool 12, or rewound thereon, 85 without catching of the friction-shoe on the sheet.

In order that the member 17, if not itself heavy enough, may be so heavy as to exert the necessary pressure of the shoe 16 upon 90 the music sheet, the lower end of said member 17 carries a weight 21. The brackets 18, at the upper end of the swinging or pivoted member 17, are provided with a series of holes 22, which extend in a direction substantially at right angles to the plane of the member 17, said holes being adapted to receive the pivot-pins 19, which pins are removable from one set of coinciding holes, and may be engaged in another set of coinciding holes, said pins being screw-threaded at their inner ends to screw into the box 10, or the said box may be provided with complementary holes. The holes 22 and the adjustable pins 19, enable the pivot-points for the member 17 to be changed, so 95 that the weight will exert more or less pressure of the shoe 16 on the roll of music, 100 105 de-

pending upon the position of said pins. It will be noted that the construction shown will not permit the member 17 to move further than to a vertical position, and such a construction is preferable.

In Fig. 3 there is indicated by the broken line *p*, the direction of thrust or pressure of the friction-shoe 16, upon the roll of sheet music which is on the spool 12, and it will be noticed that the pressure is exerted on a line which extends substantially along a chord of the circular cross-section of the spool, or to one side of the longitudinal center of the spool 12, and between said center and the spool 14. The reason for this direction of pressure is that when the web or sheet of music is being unwound from the spool 12 in playing, there is a tendency to impart a greater friction or braking effect than when the roll is being rewound in opposite direction from the roll 14. It will also be noted that when a large roll is placed upon the rotary carrier or spindle 13, that the member 17 and its weight will be pushed far back, and the further the same are pushed back towards a horizontal position, the more strongly will the friction-shoe act upon the perforated sheet of music being unwound in playing. As the roll is played and diminishes in size, the braking effect becomes gradually less, so that, at the beginning of a tune there is a strong braking effect, and at the end there is a lighter one. The result is that when the perforated web is wound hard upon the spool 14, at the beginning, and lighter toward the end, diminishing lighter, the suction across the tracker-bar 11, will not cause the web or sheet on the lower spool to slip with a jerk and wind up harder when a loud passage is being played.

The shoe 16 and the member 17 of the brake, as shown, are supposed to be of wood, but it is obvious that, properly constructed, the said parts may be of metal, but in either case the friction-surface 20 of the shoe should be polished smoothly so as not to injure or tear the perforated sheet.

It will be obvious to those skilled in the art that the construction shown and described is susceptible of considerable modification, without departing from the scope of the claims, as, for example, the back of the spool-box might be stationary, and the brake project through an opening therein.

What we claim as new is:

1. In braking means for perforated music rolls, the combination with a support provided with a rotary music-roll carrier, of a brake pivotally hung from said support, above said carrier, and having a friction-shoe projecting forwardly and positioned to act upon and towards a part carried by said carrier, in a direction to one side of the axis of rotation of said part, said shoe when in

action being held against movement laterally of the said direction in which it acts.

2. In braking means for perforated music rolls, the combination with a support provided with parallel, rotary carriers, each adapted to act as a let-off and a take-up carrier, of a two-way brake pendently hung from said support and having a friction-shoe located in juxtaposition to that one of said carriers which constitutes a let-off in playing the music, and positioned to act between the axes of said carriers, upon and towards the music roll on said juxtaposed carrier, substantially along a chord of the circular cross-section of the said roll, said brake being arranged behind said carriers, and the point from which said brake is hung being located above the juxtaposed carrier.

3. In braking means for perforated music rolls, the combination with a support and a music-roll mounted rotatably thereon, of a brake having a friction-shoe constructed and arranged to act directly on the surface of the web of the music-roll with a greater braking effect when the perforated web is moving forward in playing than when said web is being rewound, said shoe being held against movement laterally of the direction of its said action.

4. In braking means for perforated music rolls, the combination of a pair of rotatably supported carriers, a music-roll on one of said carriers, which forms a let-off carrier in playing, while the other then forms a take-up carrier for the web of music, and a gravitating brake pivotally hung above the said let-off carrier, having a friction-shoe arranged behind said let-off carrier and positioned to act on the surface of said roll with a decreasing braking action while the roll is being unwound, and to act on said roll with a less braking action when the web of music is moving in a reverse direction in rewinding.

5. In braking means for perforated music rolls, the combination of a box forming a support, a pair of carriers supported, rotatably, one above the other in said box, the music-roll supported on one of said carriers, and a gravitating brake pivotally hung from said box at a point above the upper carrier, and, at its lower end, having a friction-shoe arranged behind said carriers in a position to act forwardly in a direction between the axes of said carriers but adjacent the upper carrier, whereby, when the upper carrier constitutes a let-off and the lower carrier a take-up, the said shoe will bear on said roll with a gradually-decreasing braking effect, but with a greater braking effect than when the lower carrier constitutes a let-off and the upper carrier a take-up.

6. In braking means for perforated music rolls, the combination with a rotary music

roll carrier, of a pivotally-hung brake having a friction-shoe positioned to act substantially along a chord of the roll on said carrier and being independent of the rotary motion of said carrier excepting for its movement in the direction of its said action.

7. In braking means for perforated music rolls, the combination with a support and a 10 music roll mounted rotatably thereon, of a brake having a friction-shoe constructed and arranged to act on the surface of the music roll on a line to one side of the axis of said roll with a gradually diminishing 15 effect as the music sheet is moved forward in playing, said shoe being fixed against movement laterally of the direction of its said action.

8. In braking means for perforated music 20 rolls, the combination with a spool-box provided with a rotary music roll carrier, of a brake hung at a point above the roll to be supported by said carrier, and, below said point, having a rigid friction-shoe arranged 25 behind the vertical plane of, but adjacent, said carrier, in a position to act forwardly

in a line below the axis of said carrier but adjacent said roll, whereby said shoe will bear on said roll with a gradually decreasing braking effect when said roll acts as a 30 let-off roll for the perforated web.

9. In braking means for perforated music rolls, the combination of a support, a rotary music roll carrier, a brake pivotally suspended from said support and having a 35 friction-shoe, and provided with means for urging said shoe forwardly towards and against the music roll supported on said carrier, the line of action of said shoe passing beneath the longitudinal axis of said roll. 40

10. In braking means for perforated music rolls, the combination, with a rotary music roll carrier, of a pivoted brake comprising a rigid friction-shoe arranged behind the vertical plane of said carrier in 45 a position to act forwardly upon the music roll supported by said carrier.

Signed at Cambridge, in the county of Middlesex and State of Massachusetts this 29th day of September, A. D. 1919.

WILLIAM A. WATSON.
WARNER EUSTIS.
